UNITED STATES PATENT OFFICE.

FREDERICK J. EDGARS, OF BROOKLYN, NEW YORK.

DESIGN FOR A WOODEN BOX.

SPECIFICATION forming part of Design No. 24,033, dated February 12, 1895.

Application filed January 17, 1895. Serial No. 535,278. Term of patent 7 years.

To all whom it may concern:

Be it known that I, FREDERICK J. EDGARS, a citizen of the United States, residing at Brooklyn, in the county of Kings and State 5 of New York, have invented a Design for a Round Wooden Box, of which the following is a specification.

The leading feature of this design for a round wooden box consists in the curved co-
10 noidal top and convex edge and ribs and com-
pound curved sides and ribbed base.

In the drawings Figure 1, is an elevation partially in section, and Fig. 2, is a plan of the same.

The top *a*, is curved and conoidal and the 15 edge *b*, of the top is convex and the ribs *c*, intervene between the portion *b*, and the compound curved sides *d*, and the projecting ribs *e*, form the base.

I claim—

The design for a wooden box substantially 20 as described and shown.

Signed by me this 12th day of January, 1895.

FREDERICK J. EDGARS.
